TENS-TRANSFER ARRANGEMENT FOR
CALCULATING MACHINESPaul Thevis, Oberndorf (Neckar), Germany, assignor to
Olympia Werke AG., Wilhelmshaven, Germany

Filed Mar. 1, 1960, Ser. No. 12,122

Claims priority, application Germany Mar. 3, 1959
19 Claims. (Cl. 235—137)

The present invention relates to a tens-transfer arrangement for calculating machines, and more particularly to a tens-transfer arrangement capable of simultaneously effecting tens-transfers in all orders where tens-transfer operations are necessary.

It is one object of the present invention to provide a tens-transfer arrangement in which all tens-transfer operations are performed in the shortest possible time.

Another object of the present invention is to provide a rapidly operating tens-transfer arrangement of simple construction which can be used in calculating machines of the type in which the totalizer remains in operative connection with the denominational members which sense the pin carriage after transfer of a numerical value, whereupon the required tens-transfer operations are carried out.

Another object of the present invention is to provide a tens-transfer arrangement in which tens-transfer elements of a series of successive orders in which the digit "9" is registered during an additive operation, are coupled together to perform a simultaneous tens-transfer operation when the tens-transfer element of the lowest order of the series requires a tens-transfer operation.

With these objects in view, one embodiment of the present invention comprises a set of totalizer pinions respectively related to denominational orders and preferably meshing with gear members which are capable of sensing a pin carriage; a set of movable tens-transfer elements, each tens-transfer element being related to a denominational order and including a locking means movable between a locking position arresting the respective tens-transfer elements and a releasing position permitting movement of the tens-transfer element, coupling means movable between an inoperative position and a coupling position for coupling the respective tens-transfer element to the tens-transfer element of the next lower order and being operatively connected to and controlled by a tens-transfer projection on the respective totalizer pinion to assume the coupling position when the pinion is in a position preceding the tens-transfer position thereof, and to assume the inoperative position when the pinion turns further to a tens-transfer position, each tens-transfer element being operatively connected to the totalizer pinion of the next higher order for movement with the same; and actuating means operatively connected to the tens-transfer elements and urging the same to move first in one direction to effect a tens-transfer operation, and then in the opposite direction to return the tens-transfer elements to the initial position.

The coupling means are operatively connected to the locking means and control the same so that the locking means assume the releasing position when the coupling means assumes the coupling position. In this manner, tens-transfer elements released by the locking means and belonging to a series of successive orders move simultaneously if the coupling means of the lowest order of the series assumes its inoperative position. Such simultaneous movement of the tens-transfer elements is transferred to the totalizer pinions which perform the necessary tens-transfer steps to assume the next following position.

In the preferred embodiment of the present invention, each tens-transfer element includes a segment-shaped supporting element on which the locking means and cou-

2

pling means are mounted for turning movement. Gear members sense the positions of the pins of the pin carriage, and mesh with the totalizer pinions when the same are shifted to an operative meshing position. Second coupling means are mounted on the supporting elements of the tens-transfer elements, and are movable to a coupling position in which they couple the tens-transfer elements to the gear members. The movement of the second coupling means to coupling position is obtained by a stationary shifting means which turns the second coupling means to the coupling position when the respective tens-transfer element starts its movement under control of the actuating means.

The actuating means preferably include springs secured to the supporting elements of the tens-transfer elements, and an actuating bar blocking the tens-transfer elements against movement under control of the springs, so that the tens-transfer elements only move when the actuating bar is moved in one direction. Movement of the actuating bar in the opposite direction returns the tens-transfer elements to the initial position. The actuating means are controlled by the operating means of the calculating machine to perform a movement in one direction during one part of the cycle of the calculating machine, and the movement in the opposite direction during the second part of the cycle of the calculating machine.

A particularly compact construction is obtained, when the actuating bar is turnably mounted on a shaft which supports the supporting elements of the tens-transfer elements, as well as the gear members, for turning movement.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary side view illustrating a tens-transfer arrangement according to the present invention in an initial position;

FIG. 2 is a fragmentary side view of a tens-transfer element according to the present invention in another operational position;

FIG. 3 is a fragmentary perspective view illustrating the tens-transfer arrangement of the present invention; and

FIG. 4 is a fragmentary side view on an enlarged scale illustrating a detail of FIG. 1 in another operational position.

Referring now to the drawings, a shaft 1 extends through the calculating machine, and supports a set of gear members in the form of toothed segments 2 which are respectively associated with different denominational orders. Each gear member 2 has a projecting arm 2a, and is urged by a spring 9 to turn in counterclockwise direction as viewed in the drawing to the initial position illustrated in FIG. 1 in which all gear members 2 abut an abutment member 10. During the operation of the calculating machine, the abutment member 10 is lowered so that the gear members 2 sense in a conventional manner the shifted pins 11 of a pin carriage 12. After the sensing operation is completed, the abutment member 10 returns the gear members 2 to the initial position shown in FIG. 1.

Two totalizers I and II are provided. The totalizer I has in each order an additive pinion 3, and a subtractive pinion 4, and the totalizer II has in each order an additive pinion 5 and a subtractive pinion 6. The totalizer elements are shiftable in a conventional manner so that either the additive pinions 3 and 5, or the subtractive

pinions 4 and 6, mesh with the respective gear members 2. Pinions 3, 4, and 5, 6, respectively, are mounted on supports which permit axial shifting of the pinions into a position exactly aligned with the gear members 2.

Gear members 2 also mesh with gear segments 7 of a printing means which are mounted on a movable support 8 by which the printing means can be moved into and out of meshing engagement with the respective gear members 2. While the gear segments 7 are in meshing engagement with gear members 2, the respective digital values registered in the same are transferred to the printing means, and the printing means can be moved out of meshing engagement with gear members 2 to a printing position in which the corresponding numerical value is printed.

A tens-transfer element is provided for each decimal order, except the highest order, and is located between two adjacent gear members 2. Each tens-transfer element includes a supporting element 13 which is mounted for turning movement on shaft 1. A coupling means is mounted on each supporting element 13, and includes a pair of levers 14 and 15, each of which is pivotally mounted on the supporting element 13. Coupling lever 14 has a fork-shaped end portion into which a pin of the other lever 15 projects so that levers 14 and 15 are articulated to each other for turning movements in opposite directions.

Coupling lever 14 has a projection 14b projecting to the left as viewed in FIG. 3 and toward the tens-transfer element of the next lower order. A pin 14a on coupling lever 14 projects to the right as viewed in FIG. 3 and toward the tens-transfer element of the next higher order.

Lever 15 has a projection 15b cooperating with a projection 16b on a locking means 16 which is turnably mounted on the respective supporting element 13. A spring 19 connects locking means 16 with an arm of lever 15.

As best seen in FIG. 1, locking means 16 is urged by spring 19 into a locking position engaging a blocking means 18 which extends parallel to shaft 1 through openings in all gear members 2 and supporting elements 13. When a locking means 16 is in the locking position illustrated in FIG. 1, the respective tens-transfer element cannot turn. In the releasing position of locking means 16 shown in FIG. 2, the respective tens-transfer element is released for turning movement in clockwise direction, but such turning is blocked by an actuating bar 24 when the same is in the position shown in FIG. 1. Actuating bar 24 extends through openings in all gear members 2 and supporting elements 13, and is a part of an actuating member which is mounted for turning movement on shaft 1, and is controlled by the operating means of the calculating machine to perform reciprocating movements about the axis of shaft 1.

Locking means 16 has a projection 16c cooperating with a catch lever 17 which is turnably mounted on the supporting element 13, and is biased by spring 20 to engage the projection 16c as long as locking means 16 is in the locking position illustrated in FIG. 1.

A set of pivoted levers 26 is mounted on a shaft 28, and a set of pivoted levers 27 is mounted on a shaft 29. A spring 30 connects levers 26 and 27 of each pair, and urges the same against a stop shaft 31.

In the initial position illustrated in FIG. 1, one arm of lever 26 is located opposite the pin 14a, but spaced from the same, and an arm of lever 27 is located opposite pin 15a, but spaced from the same.

Levers 26 and 27 are respectively associated with the pinions 3, 4 and 5, 6 of the totalizers I and II. Each pinion 3, 4, 5 and 6 has a tens-transfer projection 3a, 4a, 5a, 6a, respectively, which laterally projects from the pinion, so that the tens-transfer projections of the pinions are located in the plane of levers 26 and 27, while the pinions 3, 4, 5, 6 are located in the plane of the re-

spective gear members 2. When one of the totalizers is moved to the position shown in FIG. 4, one of the pinions, for example, the additive pinion 3, meshes with the gear member 2 of the same order, while the respective tens-transfer projection 3a will engage an arm of lever 26 when the tens-transfer projection 3a is in the illustrated position, which corresponds to the position of pinion 3 preceding a tens-transfer, and consequently associated with the digit "9" for the additive pinion 3.

The tens-transfer projections 5a and 6a of pinions 5 and 6 will cooperate in the same manner with an arm of lever 27 if pinion 5 or pinion 6 is moved into meshing engagement with the respective gear member 2. When a tens-transfer projection, for example projection 3a, engages lever 26 as shown in FIG. 4, lever 26 performs a short pivotal movement and acts on pin 14a so that coupling lever 14 turns in clockwise direction to the coupling position shown in FIG. 4 in which the coupling projection 14b is located opposite a projection 13a of the supporting element 13 of the tens-transfer element of the next lower order, so that the tens-transfer element of the actuated coupling lever 14 is coupled to the tens-transfer element of the next lower order for turning movement about shaft 1. When the pinion 3 moves to the next following tens-transfer position, projection 3a releases lever 26 which returns to its normal position under the action of spring 30, while coupling lever 14 is turned by lever 15 under the action of spring 19 to its inoperative position shown in FIG. 1 in which coupling projection 14b is not located opposite projections 13a of the tens-transfer element of the next lower order. Therefore, the two tens-transfer elements are not coupled in the position of FIG. 1, or in the tens-transfer position shown in FIG. 2 in which the tens-transfer projection 3a has moved one step beyond lever 26.

The short displacement of coupling means 14, 15 effected by the tens-transfer projection 3a passing through the position preceding the tens-transfer position, effects turning of locking means 16 from the locking position shown in FIG. 1 to the releasing position shown in FIG. 2. During the short displacement of coupling means 14, 15, projection 15b engages projection 16b of locking means 16 and turns locking means 16 in clockwise direction as viewed in FIG. 1 against the action of spring 19. Therefore, locking means 16 would return to its initial locking position when the coupling means 14, 15 are returned to the initial position, but catch means 17 locks locking means 16 in the releasing position by engaging projection 16c in a corresponding cutout so that locking means 16 remains in the releasing position releasing blocking means 18 as shown in FIG. 2. At the end of the cycle of operation of the calculating machine, a clearing means 25, which extends in axial direction through openings in gear members 2 and supporting elements 13, is operated to shift catch means 17 to a position releasing projection 16c, so that the locking means 16 can return to its locking position under the control of spring 19.

In addition to the first coupling means 14, 15, which couple adjacent tens-transfer elements, second coupling means 21 are provided for coupling each supporting element 13 of a tens-transfer element to the gear member 2 of the next higher order.

The coupling lever 21 is pivotally mounted on the supporting element 13 and has at one end a projection 21b cooperating with an inner projection on the gear member 2 of the next higher order. The other arm of coupling lever 21 has an elongated recess 21c, and a projecting portion 21a. A spring 22 is attached to each coupling lever 21 and extends at such an angle that it not only turns lever 21 to the position illustrated in FIG. 1, but also urges the respective supporting element 13 to turn in clockwise direction into a position abutting the actuating member 24 which extends through an opening 13b in all supporting elements. As long as supporting element 13 abuts

actuating bar 24, it cannot turn under the action of spring 22, even if released by locking means 16 in the releasing position shown in FIG. 2. However, when actuating bar 24 moves away from the respective spoke of supporting element 13, as shown in FIG. 2, springs 22 will turn tens-transfer elements whose locking means 16 are in releasing position.

A shifting means in the form of a bar 23 extending through the openings in gear members 2 and supporting elements 13, is provided to effect shifting of the second coupling means 21 from the inoperative position shown in FIG. 1 to the position coupled to the gear member 2 of the next higher order, as shown in FIG. 2.

When the actuating member turns about shaft 1, and the actuating bar 24 moves in clockwise direction out of the position shown in FIG. 1, supporting elements 13 whose locking means 16 are in releasing position will start to turn in clockwise direction under the action of springs 22. During such movement, shifting bar 23 will move into the respective recess 21c, so that the respective coupling lever 21 can turn in counterclockwise direction through a small angle so that during further turning movement of supporting element 13, projection 21b engages projection 2b of the gear member 2 of the next higher order. In this position, projection 21a of lever 21 is located between the shifting bar 23 and the actuating bar 24. While the spring 22 is too weak to overcome the force of spring 9, further movement of the actuating bar 24 will effect not only turning of the respective supporting element 13 but also turning of the gear member 2 of the next higher order through coupling means 21, 21b acting on projection 2b.

The tens-transfer apparatus operates in the following manner: In the initial position shown in FIG. 1, the totalizers I and II are retracted so that no pinion meshes with the gear member 2. A numerical value is introduced in a conventional manner into the pin carriage 12, whereupon the abutment member 10 is turned in counterclockwise direction about shaft 1 to a lower position permitting gear members 2 to turn in counterclockwise direction under the action of springs 9 to a sensing position in which projections 2a abut projecting pins 11 of the pin carriage which respectively represent digits in the order of the pin carriage. The angular displacements of gear members 2 are proportional to the digits introduced into the respective orders of the pin carriage.

The gears 7 of the printing means turn through corresponding angles, so that the printing wheels assume a corresponding position. Levers 8 are now turned in clockwise direction, so that the registered value can be printed.

The totalizer I may now be moved to a position in which the additive pinions 3 mesh with the gear members 2 of the corresponding orders, and when the abutment member 10 is turned in clockwise direction during the second half of the cycle of the calculating machine, the gear members 2 are moved through different angular distances to the initial position shown in FIG. 1. The meshing pinions 3 are correspondingly turned, so that the respective numerical value is added in totalizer I. This operation is known, and not an object of the present invention.

Assuming that the value "16" is to be added to a value "34" which is already registered in totalizer I, pinion 3 of the unit order is turned in counterclockwise direction through the position representing the digit "9" to the position representing the digit "0."

While pinion 3 passes through the position representing the digit "9," the tens-transfer projection 3a engages lever 26, and pivots the same in clockwise direction so that it engages pin 14a of coupling lever 14 whereby coupling lever 14 is turned in clockwise direction, and lever 15 is turned in counterclockwise direction. Projection 15b engages locking means 16 and turns the same in clockwise direction so that projection 16c is arrested in the recess

17a of catch means 17. Locking means 16 is arrested in the position releasing blocking means 18, while coupling means 14, 15, and lever 26 return to the initial position illustrated in FIGS. 1 and 2, which is possible since tens-transfer position 3a is no longer located in the region of lever 26.

The cyclic operation of the calculating machine continues, and effects turning of actuating member 24 in clockwise direction about shaft 1 whereby all tens-transfer elements, and more particularly, the supporting elements 13 are released by actuating member 24. All tens-transfer elements whose locking means are in the releasing position shown in FIG. 2, and which are not locked by coupling engagement between projection 14b and projection 13a, as will be explained hereinafter in greater detail, can now turn to follow actuating member 24. In the example "34" plus "16," only the tens-transfer element of the unit order is released as explained above. Coupling lever 21 slides along shifting bar 23 until the recess 21c is located opposite shifting bar 23. In this moment, coupling lever 21 turns in counterclockwise direction, projection 21a is placed in the path of actuating bar 24, while projection 21b is located opposite projection 2b of gear member 2 of the next higher order, which is the second decimal order in the example. The force of spring 22 is insufficient to turn gear member 2 of the second decimal order against the action of the respective spring 9. When the actuating bar 24 moves further, it engages projection 21a and turns not only supporting element 13, but also gear member 2 of the second decimal order until projection 21a abuts shifting bar 23. The turning gear member 2 of the second decimal order has turned the pinion 3 of the same order in additive sense, to the next following position whereby a unit is added in the second decimal order, corresponding to a tens-transfer. The respective gear member 2 is now in the position shown in FIG. 2 and spaced from the abutment member 10. However, the position of the tens-transfer projection 3a in FIG. 2 does not correspond to the above explained numerical example.

After one or several tens-transfers have been carried out in the above described manner, the totalizer I is retracted in a known manner so that pinions 3 no longer mesh with gear members 2. The calculating machine continues its conventional cycle, and the actuating member 24 is moved in counterclockwise direction so that coupling means 21 releases the respective gear member 2 of the next higher order, permitting the same to turn under the control of spring 9 to the initial position abutting the abutment member 10. Actuating member 24 engages a spoke of displaced supporting elements 13, and turns the same in counterclockwise direction against the action of springs 22 to the initial position shown in FIG. 1. Finally, the clearing means 25 is moved in outward radial direction as viewed in FIG. 1, turning catch means 17 in counterclockwise direction so that locking means 16 is released, and assumes its locking position engaging blocking bar 18 under the force of spring 19.

In the above example, a tens-transfer was required only in a single order. A simultaneous tens-transfer in several orders in accordance with the present invention will now be described with reference to another example. Assuming that the number "6" is to be added to the number "997," the tens-transfer will take place from the unit order to the second decimal order in the manner described above with reference to the first example. However, the pinions of the totalizer in the second and third order are in a position representing the digit "9," and consequently, a series of tens-transfer operations from the second order to the third order and from the third order to the fourth order is required until the result "1003" is obtained.

As explained above, the tens-transfer projections 3a, 5a, 6a are arranged on the respective pinions in such a manner that they effect shifting of the coupling means

14 and 15 through levers 26 or 27 when the respective pinion is in the position preceding the tens-transfer position, and represents the digit "9."

In the position illustrated in FIG. 4, the tens-transfer projections 3a of the second and third decimal orders hold lever 26 in a displaced position in which the coupling member 14 is in coupling position so that the coupling projection 14b is located opposite the projection 13a of the supporting element 13 of the tens-transfer element of the next lower order. Since the coupling means 14, 15 is moved to coupling position, locking means 16 is in releasing position, and is held by catch 17 in releasing position.

During the cyclic operation of the calculating machine, actuating member 24 is moved in clockwise direction, as described above and releases all supporting elements 13 so that springs 22 tend to turn them in clockwise direction.

Projection 14b of coupling means 14 of the third decimal order on the tens-transfer element of the third decimal order engages projection 13a of supporting element 13 of the second decimal order, and projection 14b of coupling means of the second decimal order mounted on the supporting element 13 of the second decimal order, engages projection 13a of supporting element 13 of the unit order.

Consequently, the tens-transfer elements of the second decimal order and of the third decimal order cannot turn as long as the tens-transfer element of the unit order is locked which is the case when the locking means 16 of the unit order is in locking position engaging blocking bar 18.

In the present example, the pinion 3 of the unit order has passed through the position "9" effecting release of the locking means 16 in the unit order, and has then moved on to the position "0" in which a tens-transfer is required, and further to the position "3." Since the locking means of the unit order is also released, the tens-transfer element 13 of the unit order follows actuating bar 24, so that the tens-transfer elements of the second and third orders, which are coupled to the tens-transfer elements of the next lower orders, also turn. When the recesses 21c of the coupling levers 21 are simultaneously located opposite shifting bar 23, all coupling levers of released tens-transfer elements simultaneously turn in counterclockwise direction, so that the gear members 2 of the respective next higher orders are coupled to the turning tens-transfer elements resulting in turning of gear members 2 of the second, third and fourth decimal order through an angular distance corresponding to a unit in the respective next higher order.

In the above example, the totalizer I will register the value "993" before the tens-transfer operation is initiated by the actuating member 24; after the tens-transfer operation has been completed, the totalizer is shifted one position in the second, third and fourth decimal order, and registers "1003."

Assuming now that the number "2" is to be added to the number "997," the result is "999," so that no tens-transfer is required. During the conventional additive operation, levers 26, coupling means 14, 15, locking means 16, and catch means 17 are actuated in the unit order, and in the second and third decimal order. Projection 14b of coupling means 14 of the third decimal order is coupled to the projection 13a of the tens-transfer element of the second decimal order, projection 14b of coupling means 14 of the second decimal order is located opposite projection 13a of the tens-transfer element 13 of the unit order, and projection 14b of coupling means 14 of the unit order is located opposite a stationary stop whose position corresponds exactly to the position of the projections 13a of the supporting elements 13 of the tens-transfer elements.

When the tens-transfer elements are released by the actuating member 24, they cannot turn under the action

of springs 22, since each tens-transfer element can only turn if the tens-transfer element of the next lower order, to which it is coupled, also turns. Since the lowest order, namely the unit order, is blocked by the stationary stop 5 means, the tens-transfer elements of the second and third decimal order cannot turn.

It will be understood that this effect takes place whenever the digits "9" are registered in a series of orders. Although the respective tens-transfer elements are released by the locking means, they can only turn if the tens-transfer element of the lowest order of the series is released for movement, since all tens-transfer elements of a series of orders are coupled to each other when the digit "9" is registered in the respective orders. However, 10 if the tens-transfer element of the lowest order of a series is released and requires a tens-transfer operation, the tens-transfer operation in the following higher orders of the series are simultaneously carried out, since all tens-transfer elements of the series are coupled to each other.

15 It will be understood that each of the elements described above, or two or more together, may also find a useful application in other types of tens-transfer arrangements for calculating machines differing from the types described above.

20 While the invention has been illustrated and described as embodied in a tens-transfer arrangement for effecting simultaneous tens-transfer operations in several successive orders, it is not intended to be limited to the details shown, since various modifications and structural changes 25 may be made without departing in any way from the spirit of the present invention.

Without further analysis, the foregoing will so fully reveal the gist of the present invention that others can by applying current knowledge readily adapt it for various 30 applications without omitting features that, from the standpoint of prior art, fairly constitute essential characteristics of the generic or specific aspects of this invention and, therefore, such adaptations should and are intended to be comprehended within the meaning and range of 35 equivalence of the following claims.

40 What is claimed as new and desired to be secured by Letters Patent is:

1. Tens-transfer arrangement comprising, in combination, a set of totalizer pinions respectively related to denominational orders, each pinion having a tens-transfer projection; a stationary blocking means; a set of movable tens-transfer elements, each tens-transfer element being related to a denominational order and including a locking means movable between a locking position engaging said blocking means, and a position releasing said blocking means and permitting movement of the respective tens-transfer element, said locking means being operatively connected to the corresponding tens-transfer projection to assume said releasing position when the corresponding pinion is in a position preceding a tens-transfer position, 45 first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, and 50 second coupling means movable between an inoperative position and a coupling position for operatively coupling the respective tens-transfer element to the pinion of the next higher order; and actuating means operatively connected to said tens-transfer elements and urging the same to move a selected 55 distance when said second coupling means is in said coupled position so that tens-transfer elements released by said locking means and belonging to a series of successive orders move simultaneously if the first coupling 60 means of the lowest order of the series assumes said inoperative position.

65

60

65

70

75

operative position whereby turning of the pinions of the respective next higher orders to the next following position is effected through said second coupling means.

2. Tens-transfer arrangement comprising, in combination, a set of movable toothed members; a set of totalizer pinions respectively related to denominational orders and having a position meshing with said toothed members, each pinion having a tens-transfer projection; a stationary blocking means; a set of movable tens-transfer elements, each tens-transfer element being related to a denominational order and including a locking means movable between a locking position engaging said blocking means, and a position releasing said blocking means and permitting movement of the respective tens-transfer element, said locking means being operatively connected to the corresponding tens-transfer projection to assume said releasing position when the corresponding pinion is in a position preceding a tens-transfer position, first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, and second coupling means movable between an inoperative position and a coupling position for coupling the respective tens-transfer element to the toothed member of the next higher order; and resilient actuating means operatively connected to said tens-transfer elements and urging the same to move a selected distance when said second coupling means is in said coupled position so that tens-transfer elements released by said locking means and belonging to a series of successive orders move simultaneously if the first coupling means of the lowest order of the series assumes said inoperative position whereby through said second coupling means and said toothed members turning of the pinions of the respective next higher orders to the next following position is effected.

3. Tens-transfer arrangement comprising, in combination, a set of movable toothed members; a set of totalizer pinions respectively related to denominational order and having a position meshing with said toothed members, each pinion having a tens-transfer projection; a stationary blocking means; a set of movable tens-transfer elements, each tens-transfer element being related to a denominational order and including a locking means movable between a locking position engaging said blocking means, and a position releasing said blocking means and permitting movement of the respective tens-transfer element, said locking means being operatively connected to the corresponding tens-transfer projection to assume said releasing position when the corresponding pinion is in the position preceding a tens-transfer position, first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, and second coupling means movable between an inoperative position and a coupling position for coupling the respective tens-transfer element to the toothed member of the next higher order; shifting means for shifting said second coupling means to said coupling position during movement of the respective tens-transfer element; and actuating means including resilient means connected to said tens-transfer elements and urging the same to move a selected distance, and an actuating member normally blocking said tens-transfer elements and being movable in one direction to a releasing position

in which tens-transfer elements released by said locking means and belonging to a series of successive orders move simultaneously if the first coupling means of the lowest order of the series assumes said inoperative position so that said shifting means moves the respective second coupling means to said coupling position, said actuating member engaging during further movement thereof said second coupling means in said coupling position for further moving the released tens-transfer elements to effect through said second coupling means and said toothed members turning of the pinions of the respective next higher orders to the next following position.

4. An apparatus as set forth in claim 3, wherein said resilient means are a plurality of springs, each spring being connected to one second coupling means for urging the same to said coupling position, and for urging the respective tens-transfer element through said second coupling means to move, when released.

5. Tens-transfer arrangement comprising, in combination, a set of gear members; a shaft supporting said gear members for turning movement; an abutment member; spring means urging said gear members against said abutment member; a set of totalizer pinions respectively related to denominational orders and having a position meshing with said gear members, each pinion having a tens-transfer projection; a stationary blocking means extending parallel to said shaft; a set of tens-transfer elements supported on said shaft for turning movement, each tens-transfer element being related to a denominational order and including a locking means movable between a locking position engaging said blocking means, and a position releasing said blocking means and permitting movement of the respective tens-transfer element, said locking means being operatively connected to the corresponding tens-transfer projection to assume said releasing position when the corresponding pinion is in a position preceding a tens-transfer position, first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, and second coupling means movable between an inoperative position and a coupling position for coupling the respective tens-transfer element to the gear member of the next higher order for turning movement; shifting means including a stationary shifting bar extending parallel to said shaft for shifting said second coupling means to said coupling position during movement of the respective tens-transfer element; and actuating means including resilient means connected to said tens-transfer elements and urging the same to turn a selected angular distance, and an actuating member extending parallel to and being turnable about said shaft and normally blocking said tens-transfer elements and being movable in one direction to a releasing position in which tens-transfer elements released by said locking means and belonging to a series of successive orders move simultaneously if the first coupling means of the lowest order of the series assumes said inoperative position so that said shifting means moves the respective second coupling means to said coupling position, said actuating member engaging during further movement thereof said second coupling means in said coupling position for further moving the released tens-transfer elements to effect through said second coupling means and said gear members turning of the pinions of the respective next higher orders to the next following position.

6. An apparatus as set forth in claim 5 wherein said second coupling means includes a spring-loaded coupling lever having an elongated recess abutting said shifting bar in said coupled position, and having a projecting end

portion engaged by said actuating member during turning movement of the tens-transfer element through said selected angular distance and abutting said shifting bar to stop turning movement after the tens-transfer element has turned said angular distance.

7. Tens-transfer arrangement comprising, in combination, a set of gear members; a shaft supporting said gear members for turning movement; an abutment member; spring means urging said gear members against said abutment member; a set of totalizer pinions respectively related to denominational orders and having a position meshing with said gear members, each pinion having a tens-transfer projection; a stationary blocking means extending parallel to said shaft; a set of movable tens-transfer elements, each tens-transfer element being related to a denominational order and including a segment-shaped supporting element supported on said shaft for turning movement, a locking means mounted on said supporting element turnable between a locking position engaging said blocking means, and a position releasing said blocking means and permitting movement of the respective tens-transfer element, said locking means being operatively connected to the corresponding tens-transfer projection to assume said releasing position when the corresponding pinion is in a position preceding a tens-transfer position, first coupling means mounted on said supporting element turnable between an inoperative position and a coupling position for coupling the respective tens-transfer element to the supporting element of the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, and second coupling means mounted on said supporting element turnable between an inoperative position and a coupling position for coupling the respective tens-transfer element to the gear member of the next higher order; and resilient actuating means operatively connected to said tens-transfer elements and urging the same to turn a selected angular distance when said second coupling means is in said coupled position so that tens-transfer elements released by said locking means and belonging to a series of successive orders turn simultaneously if the first coupling means of the lowest order of the series assumes said inoperative position whereby through said second coupling means and said gear members turning of the pinions of the respective next higher orders to the next following position is effected.

8. Tens-transfer arrangement comprising, in combination, a set of movable toothed members; a set of totalizer pinions respectively related to denominational orders and having a position meshing with said toothed members, each pinion having a tens-transfer projection; a stationary blocking means; a set of movable tens-transfer elements, each tens-transfer element being related to a denominational order and including a locking means movable between a locking position engaging said blocking means, and a position releasing said blocking means and permitting movement of the respective tens-transfer element, said locking means being spring-loaded and tending to move to said locking position, catch means for arresting said locking means in said releasing position, first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, said first coupling means being operatively connected to said locking means so that the same assumes said releasing

position when said coupling means assumes said coupling position, said first coupling means being spring-loaded and tending to return to said inoperative position, and second coupling means movable between an inoperative position and a coupling position for coupling the respective tens-transfer element to the toothed member of the next higher order; clearing means for operating said catch means to release said locking means; and resilient actuating means operatively connected to said tens-transfer elements and urging the same to move a selected distance when said second coupling means is in said coupling position so that tens-transfer elements released by said locking means and belonging to a series of successive orders move simultaneously if the first coupling means of the lowest order of the series assumes said inoperative position whereby through said toothed members and second coupling means turning of the pinions of the respective next higher orders to the next following position is effected.

9. Tens-transfer arrangement comprising, in combination, a set of movable toothed members; a set of totalizer pinions respectively related to denominational order and having a position meshing with said toothed members, each pinion having a tens-transfer projection; a stationary blocking means; a set of movable tens-transfer elements, each tens-transfer element being related to a denominational order and including a locking means movable between a locking position engaging said blocking means, and a position releasing said blocking means and permitting movement of the respective tens-transfer element, said locking means being spring-loaded and tending to move to said locking position, catch means for arresting said locking means in said releasing position, first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, said coupling means being operatively connected to said locking means so that the same assumes said releasing position when said coupling means assumes said coupling position, said coupling means being spring-loaded and tending to return to said inoperative position, and second coupling means movable between an inoperative position and a coupling position for coupling the respective tens-transfer element to the toothed member of the next higher order; shifting means for shifting said second coupling means to said coupling position during movement of the respective tens-transfer element; clearing means for operating said catch means to release said locking means; and actuating means including resilient means connected to said tens-transfer elements and urging the same to move a selected distance, and an actuating member normally blocking said tens-transfer elements and being movable in one direction to a releasing position in which tens-transfer elements released by said locking means and belonging to a series of successive orders move simultaneously if the first coupling means of the lowest order of the series assumes said inoperative position so that said shifting means moves the respective second coupling means to said coupling position, said actuating member engaging during further movement thereof said second coupling means in said coupling position for further moving the released tens-transfer elements to effect through said second coupling means and said toothed members turning of the pinions of the respective next higher orders to the next following position.

10. Tens-transfer arrangement comprising, in combination, a set of gear members; a shaft supporting said gear members for turning movement; an abutment member; spring means urging said gear members against said abutment member; a set of totalizer pinions respectively re-

lated to denominational order and having a position meshing with said gear members, each pinion having a tens-transfer projection; a stationary blocking means extending parallel to said shaft; a set of tens-transfer elements supported on said shaft for turning movement, each tens-transfer element being related to a denominational order and including a locking means movable between a locking position engaging said blocking means, and a position releasing said blocking means and permitting movement of the respective tens-transfer element, said locking means being spring-loaded and tending to move to said locking position, catch means for arresting said locking means in said releasing position, first coupling means movable between an inoperative position and a coupling position for coupling the respective tens-transfer element to the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, said coupling means being operatively connected to said locking means so that the same assumes said releasing position when said coupling means assumes said coupling position, said coupling means being spring-loaded and tending to return to said inoperative position, and second coupling means movable between an inoperative position and a coupling position for coupling the respective tens-transfer element to the gear member of the next higher order for turning movement; shifting means including a stationary shifting bar extending parallel to said shaft for shifting said second coupling means to said coupling position during movement of the respective tens-transfer element; clearing means for operating said catch means to release said locking means; and actuating means including resilient means connected to said tens-transfer elements and urging the same to turn a selected angular distance, and an actuating member extending parallel to and being turnable about said shaft and normally blocking said tens-transfer elements and being movable in one direction to a releasing position in which tens-transfer elements released by said locking means and belonging to a series of successive orders move simultaneously if the first coupling means of the lowest order of the series assumes said inoperative position so that said shifting means moves the respective second coupling means to said coupling position, said actuating member engaging during further movement thereof said second coupling means in said coupling position for further moving the released tens-transfer elements to effect through said second coupling means and said gear members turning of the pinions of the respective next higher orders to the next following position.

11. Apparatus as set forth in claim 10 and including a stationary stop member located adjacent the tens-transfer element of the unit order for engaging the coupling means of the unit order in said coupling position for blocking turning movement of said tens-transfer element while the respective locking means is in said releasing position and said tens-transfer projection is in the position preceding the tens-transfer position.

12. Apparatus as set forth in claim 10 wherein said tens-transfer element includes a supporting element; and wherein said coupling means include two levers pivotally mounted on said supporting element and articulated to each other, one of said levers being a coupling lever for coupling said supporting element to the supporting element of the next lower order, and the other lever shifting said locking means to said releasing position.

13. Apparatus as set forth in claim 12 and including a set of pivoted members respectively located between each tens-transfer projection of said totalizer pinions and said coupling lever for operatively connecting said tens-transfer projection with said coupling means; said set of

totalizer pinions being movable to and from said meshing position.

14. Apparatus as set forth in claim 13 and including a second set of totalizer pinions having tens-transfer projections; another set of pivoted members operatively connecting said projections of said second set of pinions with the other levers of the respective coupling means; and wherein both sets of pinions are movable to and from said meshing position; said tens-transfer projections engaging said pivoted members only in said meshing position.

15. Apparatus as set forth in claim 13 wherein said set of pinions is in said meshing position during movement of said actuating member in said one direction, and are separated from said gear members when said actuating member is returned in the opposite direction for returning said tens-transfer elements to the initial position thereof; said clearing means being actuated during the return movement of said actuating member to release 20 said catch means so that said locking means move to said locking position and lock said tens-transfer elements.

16. Tens-transfer arrangement comprising, in combination, a set of totalizer pinions respectively related to denominational orders, each pinion having a tens-transfer projection; a supporting shaft; a stationary blocking means extending parallel to said shaft; a set of movable tens-transfer elements, each tens-transfer element being related to a denominational order and including a supporting element turnably mounted on said shaft, a locking means between a locking position engaging said blocking means, and a position releasing said blocking means and permitting movement of the respective tens-transfer element, said locking means being operatively connected to the corresponding tens-transfer projection to assume said releasing position when the corresponding pinion is in a position preceding a tens-transfer position, and first coupling means mounted on said supporting element turnable between an inoperative position and a coupling position for coupling the respective tens-transfer element to the supporting element of the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, and second coupling means movable to and from a coupling position for operatively coupling the respective tens-transfer element to the pinion of the next higher order; and actuating means operatively connected to said supporting elements and urging the same to move a selected distance when said second coupling means is in said coupling position so that tens-transfer elements released by said locking means and belonging to a series of successive orders turn simultaneously if the first coupling means of the lowest order of the series assumes said inoperative position whereby turning of the pinions of the respective next higher orders to the next following position is effected through said second coupling means.

17. Tens-transfer arrangement comprising, in combination, a set of totalizer pinions respectively related to denominational orders, each pinion having a tens-transfer projection; a supporting shaft; a stationary blocking means extending parallel to said shaft; a set of movable tens-transfer elements, each tens-transfer element being related to a denominational order and including a supporting element turnably mounted on said shaft, a locking means between a locking position engaging said blocking means, and a position releasing said blocking means and permitting movement of the respective tens-transfer element, said locking means being spring-loaded and tending to move to said locking position, catch means for arresting said locking means in said releasing position, and first coupling means mounted on said supporting element turnable between an inoperative position and a coupling

position for coupling the respective tens-transfer element to the supporting element of the tens-transfer element of the next lower order, and operatively connected to the corresponding tens-transfer projection to assume said coupling position when the corresponding pinion is in the position preceding the tens-transfer position, and to assume said inoperative position when the corresponding pinion turns further to said tens-transfer position, said first coupling means being operatively connected to said locking means so that the same assumes said releasing position when said first coupling means assumes said coupling position, said first coupling means being spring-loaded and tending to return to said inoperative position, and second coupling means movable to and from a coupling position for operatively coupling the respective tens-transfer element to the pinion of the next higher order; clearing means for operating said catch means to release said locking means; and actuating means operatively connected to said supporting elements and urging the same to move a selected distance when said second coupling means is in said coupled position so that tens-transfer elements released by said locking means and belong to a series of successive orders turn simultaneously if the first coupling means of the lowest order of the series assumes said inoperative position whereby turning of the pinions of the respective next higher orders to the next following position is effected through said second coupling means.

18. Apparatus as set forth in claim 17 wherein said supporting elements have openings, and wherein said actuating means include an actuating bar passing through the openings of said supporting elements and being supported on said shaft for movement about the same, and springs operatively connected to said supporting elements and urging the same to turn and abut said actuating bar, said bar releasing said supporting elements for turning movement under the action of said springs when moving in one direction, and returning said supporting elements to an initial position when moving in the opposite direction.

19. Apparatus as set forth in claim 18 and including a stationary stop member located adjacent the tens-transfer element of the unit order for engaging the coupling means of the unit order in said coupling position for blocking turning movement the supporting element of said tens-transfer element while the respective locking means is in said releasing position and said tens-transfer projection is in the position preceding the tens-transfer position.
